UNITED STATES PATENT OFFICE.

WILLIAM C. WHITACRE, OF ST. LOUIS, MISSOURI, ASSIGNOR TO THE WHITACRE AIR-BRAKE COMPANY, OF EAST ST. LOUIS, ILLINOIS.

TRIPLE VALVE.

SPECIFICATION forming part of Letters Patent No. 542,509, dated July 9, 1895.

Application filed March 8, 1894. Serial No. 502,802. (No model.)

To all whom it may concern:

Be it known that I, WILLIAM C. WHITACRE, a citizen of the United States, residing at the city of St. Louis, State of Missouri, have invented a certain new and useful Improvement 5 in Triple Valves, of which the following is a full, clear, and exact description, reference being had to the accompanying drawings, forming part of this specification, wherein like letters of reference denote like parts wherever they occur, and in which—

Figure 1 is a side elevation. Fig. 2 is a cross-sectional view. Fig. 3 is a detail view 15 of the two valves, and Figs. 4 to 7 are longitudinal sectional views showing the valve in different positions.

This invention relates to a new and useful improvement in triple valves for pneumatic-brake systems, and is designed to control the 20 admission of air from the train-pipe to the auxiliary reservoir and to control the admission of air from the auxiliary reservoir to the brake-cylinder and the exhaust of the brake-cylinder, as is common.

25 The special features of improvement in this improved form of triple valve reside in the peculiar formation and operation of a rotary valve, which controls the passage of the air from the train-pipe to the auxiliary reservoir, which passage is closed when communication is opened between the auxiliary reservoir and the brake-cylinder and opened when the air in the brake-cylinder is exhausted, said rotary valve being operated to accomplish this by a master-valve, which master-valve is operated by the pressure in the train-pipe to open communication between the train-pipe and the auxiliary reservoir, said master-valve being also operated by the pressure 30 in the auxiliary reservoir to open communication between the auxiliary reservoir and brake-cylinder when the pressure in the train-pipe is reduced, in providing means for causing the master-valve to move the rotary valve 35 to a "lap" position when the pressure in the auxiliary reservoir is reduced by the same passing into the brake-cylinder, which means is overcome, upon the further reduction of air in the train-pipe, to such an extent as to 40 permit the pressure in the auxiliary reservoir to actuate the master-valve to move the ro-

tary valve to a position in which the air in the brake-cylinder is exhausted.

Other minor details reside in the peculiar construction and arrangement of the several 55 parts of my improved valve, all as will hereinafter be described, and pointed out in the claims.

In the drawings, A indicates the casing, bored to two different diameters and formed with a chamber and seat in its upper end for the reception of a rotary valve. The lower end of the casing is closed by a cap B, which has a coupling formed thereon for connection with the train-pipe C, which train-pipe, as 60 shown, opens to the larger bore of the casing beneath the master-valve. Cap D closes the chamber in which the rotary valve is located. Pipe E connects the rotary valve-chamber with the auxiliary reservoir. Pipe F connects 65 the port F', located beneath the rotary valve, with the brake-cylinder. The casing is formed with ports a, leading from the space beneath the master-valve to a point in the seat of the rotary valve.

G indicates the master-valve, formed with the winged stem extending upward into the smaller bore of the casing, the valve proper operating in the larger bore. The stem of this master-valve is cored out to several diameters to receive a rod H, which rod is provided with a flange h, upon which is seated a spring I confined between the flange and the shoulder formed in the stem. The tendency 80 of this spring operating between the shoulder 85 in the valve-stem and the flange on the rod is to always force the rod outwardly, and, should the rod contact with the cap B, as shown in Figs. 5 and 7, the tendency of the rod and spring is to return the master-valve 90 to a position as shown in Fig. 6. The cap J restrains the outward movement of the rod. Attached to the upper end of the master-valve is a link K, which is also connected to the rotary valve L. By preference this link is attached in a bifurcation formed in one side of the rotary valve, so as to leave the circularity of its seat unbroken, thus permitting the wear to be even and make a more perfect seat. The rotary valve L is, as shown in Fig. 2, seated 95 on one side of the casing only, so as to permit a passage through the port N from port 100

a into the auxiliary reservoir and from the auxiliary reservoir through port *N* and port *f* or *F'* into the brake-cylinder. The pressure is thus exerted on one side of the valve 5 only and forces the valve to a close seat.

M indicates a stem received in the casing *A* and cap *D*, upon which stem is mounted rotary valve *L*.

N indicates a cross-port extending through 10 the valve *L*, and *O* indicates the capping, groove, or cross-connection formed in its under side, which connects the port *F'* (leading from the brake-cylinder) with exhaust-port *P*, formed in casing *A* and opening to the exterior. 15

The operation is as follows: Assuming that pressure is admitted into the large bore of the casing through the train-pipe, the master-valve will be forced up, unclosing port *a* and 20 revolving the rotary valve, so that port *N* will register therewith, thus establishing a communication between the train-pipe and the auxiliary reservoir. This I term the "running position" and is illustrated in Fig. 4. In this 25 position the pressure in the auxiliary reservoir is raised to equalize that in the train-pipe. Should the pressure in the train-pipe be slightly reduced in order to apply the brakes gently or cause the train to come to a 30 "service stop," the pressure in the auxiliary reservoir being in excess of that in the train-pipe and not finding a ready and quick escape back through the ports *N* and *a* will force the master-valve downwardly and revolve the 35 rotary valve, so as to close port *a* and register port *N* with an advanced port *f*, opening into the brake-cylinder port *F'*. This will open communication between the auxiliary reservoir and brake-cylinder through ports *N*, *f*, 40 and *F'*. Port *f* is a small port located in the valve-seat and leading into port *F'*, the object of which port *f* being to enable a restricted communication between the auxiliary reservoir and the brake-cylinder when the rotary 45 valve is moved, as above described, without allowing the air to rush from the auxiliary reservoir into the brake-cylinder, as would be the case if port *N* registered with the large opening of port *F'*. As the pressure passes from the 50 auxiliary reservoir to the brake-cylinder it is gradually reduced in the former, and the master-valve is not burdened with so much downward pressure as when the charging of the brake-cylinder first began. This release 55 of downward pressure on the master-valve permits spring *I* to assert itself and raise the master-valve from the position shown in Fig. 5 to the position shown in Fig. 6. This movement to the position shown in Fig. 6 causes 60 the rotary valve to so assume a position as to close all ports leading to or from the train-pipe, auxiliary reservoir, or brake-cylinder. This I term the "lap" position, and in this position the valves are held or supported by 65 rod *H* and spring *I*.

To apply the brakes quickly and with force to bring the train to an "emergency" or

"full" stop, the pressure is still further reduced or exhausted from the train-pipe, which will permit the master-valve to be forced 70 down by the pressure in the auxiliary reservoir, compressing spring *I* and forcing rod *H* upward into the stem until the master-valve reaches the limit of its downward movement. This downward movement of the master-valve rotates the rotary valve until the port *N* reaches the port *F'*, which opens full communication between the auxiliary reservoir and brake-cylinder. This position is illustrated in Fig. 7, and will be so maintained 75 until pressure is again admitted to the train-pipe in excess of the pressure in the auxiliary reservoir and brake-cylinder, when such excess pressure in the train-pipe will raise the master-valve and rotate the rotary valve until 80 port *N* registers with port *a* and communication is established between the train-pipe and auxiliary reservoir, recharging the latter for another operation, and capping or groove *O* connects port *F'* with exhaust-port *P*, leading 85 to the exterior, which will exhaust the brake-cylinder. This position is illustrated in Fig. 4.

I am aware that many minor changes in the construction and arrangement of the several parts of my valve can be made and substituted for those herein shown and described without in the least departing from the nature and principle of my invention.

Having thus described my invention, what I claim, and desire to secure by Letters Patent, is—

1. In a triple-valve, the combination with the casing formed with two different diameters, and having a seat formed in its upper end, the train pipe leading into the larger bore at the lower end, the pipe connecting the valve with the auxiliary reservoir, leading into and from the upper end of the casing at the top of the smaller bore, a port leading from the valve seat to the brake cylinder, of 105 a master-valve, operating in the bores of the casing between the train-pipe and auxiliary reservoir pipe openings, a rotary valve seated in the upper end of the casing and adapted to be operated by the movement of the master-valve, and suitable ports and cross-connections in said rotary valve for controlling the passage of air through the casing into the auxiliary reservoir and brake cylinder, and the exhaust of the brake cylinder, substantially 110 as described.

2. In a triple valve the combination with the casing, of a master-valve located therein, a spring-controlled rod *H* which projects from the lower end of the master-valve, a link *K* 115 which is connected to the upper end of the master-valve, and a rotary valve *L* located in the upper part of the casing and to which the upper end of link *K* is connected, said rotary valve being formed with a cross port *N* and 120 capping groove *O* which co-operate with ports *a*, *f*, *F'*, and *P* in the casing, substantially as and for the purpose described.

3. In a triple-valve, the combination with

- a casing provided with suitable ports and pipe connections, of a rotary valve which is formed with cross-ports and side-groove ports on its seating surface, said rotary valve being seated on one side of the casing only so as to expose one side surface and form a passage to its cross-ports, and a master valve which is connected to and operates said rotary valve, substantially as described.
4. In a triple-valve, the combination with the casing, of a master valve located therein, a rotary valve formed with a bifurcation mounted in the casing and seated on one side only thereof, and a link connection between the master-valve and the bifurcation in the rotary valve, substantially as described.

5. In a triple valve, the combination with the casing, of a master-valve located therein, a rotary valve having a link connection with, and adapted to be operated by, the master-valve, said master-valve being chambered to receive a rod H having formed thereon a flange h, spring I operating between the flange h and a shoulder in the valve, and a confining cap J, substantially as described.

In testimony whereof I hereunto affix my signature, in presence of two witnesses, this 3d day of March, 1894.

WILLIAM C. WHITACRE.
